UNITED STATES PATENT OFFICE.

WILLIAM H. FLEISCHMAN, OF BUFFALO, NEW YORK.

DESIGN FOR A CORNER-PIECE.

SPECIFICATION forming part of Design No. 29,150, dated August 2, 1898.

Application filed June 20, 1898. Serial No. 684,009. Term of patent 3½ years.

To all whom it may concern:

- Be it known that I, WILLIAM H. FLEISCHMAN, a citizen of the United States, residing at Buffalo, in the county of Erie and State of New York, have invented and produced a new and original Design for Corner-Pieces, of which the following is a specification, reference being had to the accompanying drawings, making a part thereof.
- 10 My invention relates to the shape or configuration of the corner-pieces employed for connecting the corners of frames of various kinds—such, for instance, as the frames of bed-bottoms, with their supports.
- 15 In the accompanying drawings, Figure 1 is a side elevation of a corner-piece embodying my design. Fig. 2 is an end elevation of the same. Fig. 3 is a plan of the same as it appears from above; and Fig. 4 is a cross-section in line X X, Figs. 1 and 2.

As shown in the drawings, the leading or characteristic feature of my design consists of the rectangular plate A, with a slot E through its entire thickness, the rectangular plate B, arranged along the edge of the plate A in a plane perpendicular to the plate A, and the projection C, connected with the plate B by the neck D. In form C is substantially a portion of a frustum of a cone with a hemisphere upon its smaller base, as 25 shown.

What I claim is—

The design for a corner-piece substantially as herein shown and described.

WM. H. FLEISCHMAN.
